UNITED STATES PATENT OFFICE

2,487,277

DEVICE FOR CUTTING CHANNELS IN
STONE OR MASONRY

Alexander Siftar, Vienna, Austria

Application May 23, 1947, Serial No. 750,081
In Austria June 1, 1946

7 Claims. (Cl. 125—14)

1

The invention relates to a device for cutting channels in stone and masonry and has for its object to do this work in a more exact and economic manner as has been done hitherto.

The channels required for the laying of electric conductors and piping in masonry are usually cut by hand with hammer and chisel, an operation which not only entails much labour, but does not give particularly regular results. The channels in almost every case become too large, causing unnecessary destruction of masonry, the piercing of chimneys and the use of an excessive amount of plaster.

The object of my invention is to avoid these drawbacks, to remove the dust, brought about by the work and to enable the worker to vary the width and depth of the channel as desired.

One embodiment of the device according to the invention is illustrated by way of example in the accompanying drawings in which

Figs. 1 and 2 show the device in longitudinal section and side elevation in two different operative positions.

Figs. 3 and 4 show a cross-section on line III of Fig. 1 and an end view and

Fig. 5 shows a detail to a large scale.

A housing 1 for the gearing is constructed as a carriage and is for this purpose provided at opposite sides with pairs of arms 2, 2' and 3, 3'. In the arms 2, 2' is supported an axle 4 for rollers 5 and in the arms 3, 3' a screw bolt 6 for a stirrup 7, in the side members of which is supported an axle 8 for rollers 9, 10. In the upper part of the housing main shaft 11 driven by a motor 62 is supported in longitudinal and transverse ball bearings 12, 13. A worm 14 mounted on the shaft 11 drives a worm wheel 15 of a shaft 16 connected to a spur wheel 17. The latter wheel meshes with a spur wheel 18 which is mounted on a shaft 19, as is also a spur wheel 20 which meshes with a spur wheel 21 mounted loosely on the shaft 16. The spur wheel 21 meshes with a spur wheel 22 mounted on a hollow shaft 23 which also supports the tool. The tool consists of a disc-shaped milling cutter 24 which is removably fixed on the shaft 23 by means of a key 25. The milling cutter is securely held in this position by the disc 26 of a clamping screw 27 which extends through the hollow shaft 23 and is provided at its other end with a nut and lock nut covered by a cap 28.

To the housing 1 are screwed at the places where the main shaft passes through its sides sleeves 29, 30, in which are housed coupling parts for connecting a flexible shaft and an arrange-

2

ment for removing the dust by suction. In the sleeve 29 is guided the terminal piece 31 of the sheath of the flexible shaft 32, the coupling piece 33 of which latter is pushed on to the end of the main shaft 11 and secured by a key. In order to prevent the terminal piece 31 from slipping out, there is inserted into it a spring shackle 34 which with a pin 35 engages in holes of the terminal piece 31 and of the sleeve 29.

Over the sleeve 30 is slipped the hub of a casing 36 of the arrangement for removing the dust by suction, where it is secured by means of a spring shackle 37 which engages with a pin 38 in holes in the sleeve 30 and the casing 36. The rotor 39 with the fan blades is pushed with its hub 40 on to the end of the main shaft.

The housing 1 is adapted to the space required for the gearing and to the shape of its elements and supports at the top two fork-shaped members 41, between which the handle 42 is fixed. At each end of the handle is a change-over switch 43, 43', which are so positioned that they can be actuated by the thumb for switching on the current fed to the motor through a cable 44.

In order to be able to vary the depth of the milled-in channel, the stirrup 7 supports with one of its arms a set of clutch teeth 45, for engagement with which is provided a set of counter-teeth 46 formed on a plate 47 which is fixed to the arm 3 and has a graduated arc 55. Between the other arm of the stirrup 7 and the arm 3 is a helical spring 48 on the bolt 6 and at the end of the bolt 6 on adjusting nut 49.

The axle 8 has at that end which is nearest the milling cutter a threaded collar 50, on to which the roller 10 is screwed with its hub in front of its bearing in the stirrup. The hub has an inwardly projecting annular flange 51 which forms the mark for coating with a scale 52 provided on the axle 8. On the outside surface of the roller 10 is fixable by means of a bayonet catch arrangement 53 a disc 54 which forms a wheel flange for the roller. The milling cutter is surrounded by a cup-shaped casing 56 which is fixed to the housing 1, is open at the bottom and is provided at the top with a branch 57, to which a flexible tube (not shown) leading to the casing 56 of the suction arrangement can be attached. From the suction arrangement a further flexible tube leads to a dust-collecting vessel. On the cylindrical wall of the casing 56 are slidably opposite one another two circular slide valve members 58, 59 which are stirrup-shaped and mounted so as to be capable of

swinging round the casing 56. Their cylindri-

cal central parts can, when the device is in operation, cover the opening of the casing 56 with the exception of a narrow gap, so that the suction arrangement can operate effectively. The slide valves are acted on by a spring 60 in the closing sense and bear against the surface of the masonry with rollers 67.

The device operates in the following manner:

According to the depth to which the channel is to be cut the stirrup 7 is adjusted on the graduated arc 55 which gives the depth of channel directly in millimetres, which adjustment can be effected after easing the nut 49 and turning the stirrup which is then secured in the new position by tightening the nut again. In Fig. 1 the position of the stirrup for the greatest depth of channel is shown, in the present case 25 mm. In Fig. 5 this position is shown in full lines, the adjustment to the smallest depth of channel, 5 mm., being indicated by dot and dash lines. The latter position is also shown in Fig. 2.

After the current has been switched on, the device is moved across the masonry along a marked-out line, either directly with one of the rollers or with a specially provided mark. The smallest width of channel is determined by the width of the milling cutter. In order to cut wider channels, the device is guided along an already cut channel in such a manner that the wheel flange 54 runs along one wall of the channel. The milling cutter will then, owing to its distance from the wheel flange, bite into the masonry on the other side of the channel and widen the latter. The amount of this widening can be selected by displacing the roller 10 on the threaded collar 50 along the scale 52. In the present case the maximum amount, by which the channel can be widened, corresponds to double the width of the milling cutter. In the illustration in Fig. 4, assuming the milling cutter to be 12 mm. wide, the device is set to cut a channel 18 mm. wide, that is, in the second cutting operation an additional 6 mm. will be cut out of the masonry.

Working out the channel by means of milling cutters makes it possible to limit very accurately the width and depth of the channel with the minimum expenditure of labour and waste of material. The regularity obtained is of course of advantage in the laying of the conductors.

The motor may be placed on the ground, mounted on the ladder or even carried on the back. When the device is not to be used for cutting channels in walls, but is to be run along a horizontal surface, for instance the top surface of a stone, the motor may be combined with the device.

The arrangement for removing the dust by suction enables work to be carried out without detrimentally affecting the health of the worker and without the nuisance caused by scattered dust.

The possibility of attaching the flexible shaft and the suction arrangement to either end of the main shaft at will provides the advantage of the worker being independent of the direction of rotation of the motor and therefore not bound to one direction in guiding the apparatus.

I claim:

1. A machine for cutting a groove in stones and masonry comprising a carriage adapted to travel over the surface of the stone, a rotatory cutting tool mounted on the carriage, a main shaft, speed reducing gears interposed between said main shaft and said cutting tool, identical coupling means provided at each end of said main shaft, a flexible shaft, and an exhauster,

both said flexible shaft and exhauster being adapted to be connected to either of said coupling means.

2. A machine for cutting a groove in stones and masonry comprising a carriage adapted to travel over the surface of the stone, a rotatory cutting tool mounted on the carriage, a main shaft, speed reducing gears interposed between said main shaft and said cutting tool, a flexible drive shaft coupled to one end of said main shaft, a roller connected with said carriage, said carriage comprising a housing for said reducing gears, a stirrup member pivoted to said housing, a set of rollers pivoted to said stirrup member, and a toothed clutch connected with said stirrup member for adjustably positioning it on said housing.

3. A machine for cutting a groove in stones and masonry comprising a carriage adapted to travel over the surface of the stone, a rotatory cutting tool mounted on the carriage, a main shaft, speed reducing gears interposed between said main shaft and said cutting tool, a flexible drive shaft coupled to one end of said main shaft and a roller connected with said carriage and being adjustable in axial direction, said roller having a flange extending into the groove cut by said machine.

4. A machine for cutting a groove in stones and masonry comprising a carriage adapted to travel over the surface of the stone, a rotatory cutting tool mounted on the carriage, a main shaft, speed reducing gears interposed between said main shaft and said cutting tool, a flexible drive shaft coupled to one end of said main shaft, a roller shaft connected with said carriage, a roller screwed on said roller shaft and having a flange extending into the groove cut by said machine, said roller having an extension movable freely around said roller shaft, and said shaft having a scale for determining the axial position of said extension.

5. A machine for cutting a groove in stones and masonry comprising a carriage adapted to travel over the surface of the stone, a rotatory cutting tool mounted on the carriage, a main shaft, speed reducing gears interposed between said main shaft and said cutting tool, a flexible drive shaft coupled to one end of said main shaft, an electric motor connected to and driving said flexible shaft, a handle connected with said carriage, and a change-over switch disposed on said handle and interposed in the wiring of said motor.

6. A machine for cutting a groove in stones and masonry comprising a carriage adapted to travel over the surface of the stone, a rotatory cutting tool mounted on the carriage, a main shaft, speed reducing gears interposed between said main shaft and said cutting tool, a flexible drive shaft coupled to one end of said main shaft, a roller connected with said carriage, said carriage comprising a housing for said reducing gears, a stirrup member pivoted to said housing, a set of rollers pivoted to said stirrup member, a toothed clutch connected with said stirrup member for adjustably positioning it on said housing, and position indicating means provided on said stirrup member and on said housing and indicating the relative position of said stirrup member and said housing.

7. A machine for cutting a groove in stones and masonry comprising a carriage adapted to travel over the surface of the stone and includ-

ing a casing, a main shaft and speed reduction gears driven thereby and disposed in said casing, an operating shaft driven by one of said gears and laterally protruding from said casing, a rotary cutting tool mounted on said operating shaft outside of said casing, a substantially cylindrical hood covering said cutting tool and having an opening where said cutting tool is doing the cutting, two segmental cover members connected with said hood swingably about the axis of rotation of said cutting tool for adjusting said opening in accordance with the cutting depth of said tool, and a coil spring disposed around the axis of rotation of said tool and connected with said cover members and tending to move said members in opposite directions for closing said opening.
